UNITED STATES PATENT OFFICE.

JOHN C. GOOLD, OF ALBANY, NEW YORK.

DESIGN FOR LANDAU SLEIGHS.

Specification forming part of Design No. 6,410, dated February 11, 1873.

To all whom it may concern:

Be it known that I, JOHN C. GOOLD, of the city and county of Albany, State of New York, have invented a Design for Landau Sleigh, of which the following is a specification:

The nature of my invention is fully represented in the accompanying photographic illustration, to which reference is made.

A represents the usual swell-panel body of the sleigh. B is the belt, made with the usual step-cut a, and on which is formed the back-seat arm b and front-seat arm c, all of which may be made with the forms or configurations usually employed in this class of sleighs, excepting in those parts which are parts of this design. Instead of the usual goose-neck or scroll panel-front, heretofore formed with the front portion of the sleigh, I form with the same the toe-board D, having a shape and configuration and inclination similar to that of a coach-front, in which the base of the said toe-board is made to fall in with the slightly curved line d of the front pillar-block, which rises upward and terminates with the dickey-seat C, as shown, while the nose of the runner of the sleigh is made to connect with the lower side of the said toe-board, as shown. This form or configuration of the said front of the sleigh, in lieu of the usual goose-neck or scroll panel-front, gives to the sleigh a character of style which is both novel and pleasing to the sense, and effects a relief from that sameness of form which custom has usually associated with that portion of the sleigh. I further form that portion of the sleigh between the dickey-seat C and the front passenger-seat arm c with the elliptical curved line e, commencing back of the said seat-arm, running forward and sinking below the line of the same, thence sweeping upward with an easy curve, and terminating with the lower side of the dickey-seat, as shown in the illustration. By giving to this portion of the sleigh the said shape or configuration the passenger-seat portion of the sleigh is made to present a more exclusive appearance, and the usual extensive form of the crest-panel is replaced by one more diminished, which will greatly relieve that part of the sleigh of the bulky and heavy appearance which has heretofore been presented to the eye in this class of sleighs.

Instead of the usual barouche form of top heretofore used, I form the top with the style known as the landau top, consisting of the sections E and F, as shown, which sections are arranged with the passenger-seat arms b and c, respectively, as illustrated. This form of top gives to the passenger-carrying portion of the sleigh in both its front and back seats a similarity of appearance and a show of equality for protection when the sections of the top are thrown down which cannot be had in the old barouche form of top; and by the form of the curved line e between the dickey-seat and the front passenger-seat, and the falling of the front top section into the space formed by said curved line, the said top, when let down, will in its sections appear to range with each other with great uniformity, while the dickey-seat will be made to present an appearance of separation from the passenger-carrying portion of the sleigh which will be suggestive of greater privacy to the passenger portion than has been heretofore expressed in this class of sleighs.

Having described my invention, what I claim, and desire to secure by Letters Patent, is—

1. The shape and conformation of the front portion of a swell-panel sleigh, in which the front pillar-block, leading from the dickey-seat, will, by its line d, be made to fall in with the base of the toe-board D, and the nose of the runner be made to contact with the lower side of the said toe-board, substantially as shown and described.

2. The shape and conformation of the portion of the sleigh between the dickey-seat C and the front passenger-seat or seat-arm c, in which the said portion will be made to present the curved line e, which curved line, commencing at the said seat or seat-arm, runs forward and sinks below the same, then curves upward, and terminates with the lower side of the dickey-seat, as shown and described.

3. The shape and conformation of the rear portion of the sleigh, in which the sections E and F of the top will cause both seats to present an appearance and show of similarity of protection when the sections are thrown down, as shown and described.

Witnesses: JOHN C. GOOLD.
